UNITED STATES PATENT OFFICE.

RAYMOND D. SCHNOOR, OF CHICAGO, ILLINOIS.

SIFTER.

Application filed July 31, 1924. Serial No. 729,310.

To all whom it may concern:

Be it known that I, RAYMOND D. SCHNOOR, a citizen of the United States, residing at Chicago, in the county of Cook and State of Illinois, have invented a certain new and useful Improvement in Sifters, of which the following is a full, clear, concise, and exact description; reference being had to the accompanying drawings, forming a part of this specification.

My invention has particular relation to domestic flour sifters although not limited to this use alone.

The main features of the invention reside in the provision of a simple, convenient, compact, and efficient sifter adapted for economical manufacture, affording a sturdy construction, well adapted for its purpose, susceptible of manufacture of sheet metal, and adapted for convenient assembly and disassembly.

With these features in view my invention consists in certain features of novelty in the construction, combination, and arrangement of parts by which the said features and certain other features, hereinafter appearing, are effected, all as fully described with reference to the accompanying drawings and more particularly pointed out in the claims.

In the said drawings—

Figure 1 is a side elevation of a sifter embodying my invention with parts broken away.

Figure 2 is a section on the line 2—2 of Fig. 1.

Figures 3 and 4 are side elevations of the two main assemblies of the sifter with parts broken away.

Like characters of reference indicate like parts in the several views.

Referring to the drawings 1 designates a sheet metal cylinder at one end and formed integrally with the main portion of which is a cylindrical hand hold formation 2 separated from the main portion of the frame by an inwardly projecting annular bead 3. A second sheet metal cylinder 4 has the main portion thereof nested within the cylinder 1 and has formed integrally with the main portion thereof an enlarged cylindrical hand hold formation 5 at one end thereof, which formation is provided with an annular outwardly projecting bead 6 adjacent its inner end. These cylinders are so arranged that the cylinder 4 will nest with

in the cylinder 1 with the hand hold formations 2 and 5 at opposite ends of the assemblage, and when their cylinders are so nested the ends thereof opposite those at which the aforementioned hand hold formations are disposed are adapted to respectively engage against the inside surface of the bead 3 and the inside surface of the bead 6 with the inner surface of the cylinder 1, 65 engaging the normal surface of the hand hold formation 5. See Fig. 1. Thus are provided bearings between the two cylinders disposed at opposite ends of the main portions of the cylinders, and the bead engaging ends of the cylinders are beaded in a usual manner to provide proper bearing surfaces and to strengthen these ends of the cylinders. The bearings so formed provide supports at opposite ends of the main portions of the cylinders whereby the cylinders are supported with respect to each other for angular movement and whereby the cylinders may be removed, by relative longitudinal movement, from each other.

A third sheet metal cylinder 7 is nested within the cylinder 4 and is enlarged at the end thereof adjacent the hand hold formation 2 of the cylinder 1, as designated at 8, and this enlarged end 8 is frictionally engaged in the inner portion of this hand hold formation whereby the cylinders 1 and 7 are secured together at one end. See Figs. 1 and 3. A fourth sheet metal cylinder 9 is nested within the cylinder 7 and is enlarged 90 at the end thereof adjacent the hand hold formation 5 of the cylinder 4, as designated at 11, and this enlarged end 11 is frictionally engaged in the inner portion of this hand hold formation whereby the cylinders 4 and 95 9 are secured together at the ends thereof opposite those at which the cylinders 1 and 7 are secured together. See Figs. 1 and 4.

The cylinder 4 is provided with an annular inwardly projecting bead 12 at the 100 end of the main portion thereof adjacent the hand hold formation 5, and the cylinder 7 is provided with an annular inwardly projecting bead 13 at the end of the main portion thereof adjacent the enlarged end 8 thereof. When the cylinders are nested together the end of the cylinder 7 opposite the enlarged end thereof engages the bead 12, and the end of the cylinder 9 opposite the enlarged end 11 thereof engages the bead 13. See Fig. 1. Thus are provided bearings between the cylinders 4 and 7 at

the end of the cylinder 7 opposite the end which is secured to the cylinder 1 and between the cylinders 9 and 7 at the end of the cylinder 9 opposite the end which is secured to the cylinder 4, and these bead engaging ends of the cylinders 7 and 9 are beaded in a usual manner to provide proper bearing surfaces and to strengthen these ends of the cylinders. These last mentioned 5 bearings so formed provide supports at opposite ends of the main portions of the cylinders 7 and 9 which in conjunction with the aforementioned bearings between the cylinders 1 and 4 provide supports at 10 opposite ends of the main portions of the cylinders whereby the cylinders 1 and 7 secured together and the cylinders 4 and 9 secured together are supported with respect to each other for angular movement and whereby 15 the pairs of cylinders may be removed, by relative longitudinal movement, from each other. Thus it will be observed that the cylinders are alternately secured together at respective opposite ends of the main portions 20 thereof, and that bearings are provided at the free ends thereof for supporting the cylinders with respect to adjacent cylinders for relative angular movement, the pairs of secured cylinders being removable from 25 each other by longitudinal movement. 30

A circumferentially flanged circular sheet metal closure member 14 is frictionally engaged in the outer portion of the hand hold formation 2 and closes this end of the receptacle of the sifter, this closure being provided with an exterior handle 15 whereby it may be easily removed from and installed in the hand hold formation 2. The other end of the receptacle of the sifter is closed 35 by a circular disk member 16 disposed within the hand hold formation 5 and held against the transverse wall between the main portion of the cylinder 9 and the enlarged end 11 thereof by a circumferentially 40 flanged closure member 17 frictionally engaged in the outer portion of the hand hold formation 5.

The main portions of the cylinders 1, 4, and 7 are constructed as follows to constitute cylindrical screens. The main portion of each of these cylinders is provided with a plurality of longitudinally extending openings 18 spaced around the same, these openings being preferably formed by striking out the metal 19 of the cylinders at said 50 openings with the metal 19 attached to the longitudinal sides of the openings and bending the metal 19 inwardly over the adjacent portions of the cylinders whereby to form 55 thickened portions. See particularly Fig. 2. Metal screening 21 extends around respective cylinders on the insides thereof and over said openings and is secured to respective cylinders, such as by soldering, whereby 60 to complete the cylindrical screens. The 65

thickened portions of the cylinders formed by the metal 19 being bent over the adjacent portions of the cylinders form effective agitator formations on the inner and intermediate cylindrical screens for agitating material between the screens with relative angular movement of the screens, and in addition serve to strengthen the cylinders along the openings 18. It will be observed 70 that by the construction just described the longitudinal edges of the agitator formations are rounded without necessitating additional manufacturing operations, and that the outer longitudinal edges of the metal 75 19 are covered by the screening. 80

The main portion of the inner cylinder 9 is constructed as follows to constitute a cylindrical agitator. The main portion of this cylinder is provided with a plurality of longitudinally extending openings 22 spaced around the same, these openings being preferably formed by striking out the metal 23 of the cylinder at said openings with the metal 23 attached to the longitudinal sides of the openings and bending the 85 metal 23 outwardly so that the outer longitudinal edges thereof lie adjacent the inner screen for agitating material within the receptacle of the sifter and with respect to the 90 inner screen. 95

In operation the material to be sifted is placed in the receptacle by removing the closure member 14 and placing the material within the receptacle of the sifter. After replacing the closure member 14 the sifter 100 is held by grasping the hand hold formations 2 and 5 with respective hands of the user, and these hand hold formations are given relative angular movement. This angular movement of the hand hold formations effects angular movement between the screens and between the agitator and the inner screen. The material thus agitated in the receptacle of the sifter is sifted through 105 the inner screen. Between the inner and intermediate screens the material is agitated by the agitator formations of the inner screen and is sifted through the intermediate screen. Between the intermediate screen and the outer screen the material is agitated by the agitator formations of the intermediate screen and is sifted through the outer screen of the sifter. The bearings at the ends of the screens prevent material from passing 110 by the screens at the ends thereof. 115

The screening 21 of the several screens, as shown, varies in mesh from a relatively coarse mesh on the inner screen cylinder to a relatively fine mesh on the outer screen cylinder to effect sifting of material in progressive stages. However, this arrangement is not necessary and for some purposes it is more advantageous that the graduated arrangement be either reversed or that the arrangement be of the same 120 screening of all the screens be of the same 125 130

size, mesh, as where in the sifting of flour it is desired to "fluff" the flour in the sifting thereof.

It will be observed that the construction comprises two assemblies, i. e., the agitator cylinder 9 and the intermediate screen cylinder 4 secured with the hand hold formations 5, see Fig. 4, and the inner and outer screen cylinders 1 and 7 secured with the hand hold formation 2; see Fig. 3. These two assemblies are separable and engageable by relative longitudinal movement for cleaning by reason of the construction, particularly the construction of the aforementioned bearings which are adapted to permit such movement. It will also be observed that by reason of the frictional connections between the cylinders 1 and 7 and 4 and 9 and the frictional engagement of the closure members 14 and 15 respectively with the hand hold formations 2 and 5, the cylinders 1 and 7 and 4 and 9 may be easily separated from each other and reassembled. This construction also affords convenient manufacturing assembly.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

35. 1. The combination in a sifter of a plurality of nested cylindrical screens each of which is movable with respect to the adjacent screen or screens, an agitator within the innermost screen and movable with respect thereto, and agitator formations associated with the screens for effecting agitation of material between the screens with relative movement of the screens as and for the purpose described.

45. 2. The combination in a sifter of a plurality of nested cylindrical screens each of which is movable with respect to the adjacent screen or screens, an agitator within the innermost screen and movable with respect thereto, agitator formations associated with the screens for effecting agitation of material between the screens with relative movement of the screens, said agitator and screens being alternately secured together whereby to effect simultaneous movement between adjacent screens and between the agitator and the innermost screen.

50. 3. The combination in a sifter of a plurality of nested cylindrical screens each of which is angularly movable with respect to the adjacent screen or screens, a cylindrical agitator nested within the innermost screen and angularly movable with respect thereto, said agitator and said screens being alternately secured together at respective oppo-

site ends of the screens whereby to effect simultaneous movement between adjacent screens and between the agitator and the innermost screen as and for the purpose described.

55. 4. The combination in a sifter of a cylindrical screen, an agitator therein and angularly movable with respect thereto, and hand holds at opposite ends of the screen respectively secured with the screen and agitator for effecting angular movement between the screen and agitator.

60. 5. The combination in a sifter of a plurality of nested cylindrical screens each of which is angularly movable with respect to the adjacent screen or screens, and agitator formations associated with the screens for effecting agitation of material between the screens with relative angular movement of the screens as and for the purpose described.

65. 6. The combination in a sifter of a plurality of nested cylindrical screens each of which is angularly movable with respect to the adjacent screen or screens, agitator formations associated with the screens for effecting agitation of material between the screens with relative angular movement of the screens, and hand holds at opposite ends of the screens with which the screens are alternately secured for effecting angular movement between adjacent screens.

70. 7. The combination in a sifter of a plurality of nested cylindrical screens each of which is angularly movable with respect to the adjacent screen or screens, a cylindrical agitator nested within the innermost screen and angularly movable with respect thereto, agitator formations associated with the screens for effecting agitation of material between the screens with relative angular movement of the screens, and hand holds at opposite ends of the screens with which the screens and agitator are alternately secured for effecting angular movement between the screens and between the innermost screen and the agitator.

75. 8. The combination in a sifter of a plurality of nested cylindrical screens, a cylindrical agitator nested within the innermost screen, said agitator and screens being alternately secured together at respective opposite ends of the screens whereby to effect simultaneous movement between adjacent screens and between the agitator and the innermost screen, and bearings at the free ends of the agitator and screens for supporting said agitator and screens with respect to adjacent screens for relative angular movement and adapted to prevent material passing by the screens at the ends thereof.

80. 9. The combination in a sifter of a plurality of nested cylindrical screens, a cylindrical agitator nested within the innermost screen, agitator formations associated with the screens for effecting agitation of mate-

rial between the screens with relative angular movement of the screens, said agitator and screens being alternately secured together at respective opposite ends of the 5 screens whereby to effect simultaneous movement between adjacent screens and between the agitator and the innermost screen, and bearings at the free ends of the agitator and screens for supporting said agitator and 10 screens with respect to adjacent screens for relative angular movement and adapted to prevent material passing by the screens at the ends thereof and to permit longitudinal movement of the agitator and screens with 15 respect to adjacent screens for removing said agitator and the screen or screens secured therewith from the remaining screen or screens.

10. The combination in a sifter of a cylindrical screen, a cylindrical agitator nested within the screen and angularly movable with respect thereto, bearings at opposite ends of the screen whereby the screen and agitator are supported with respect to one 20 another for relative angular movement, solid cylindrical formations at respective ends of the screen and forming hand holds and secured respectively with the screen and agitator, and circular closures frictionally engaged in said cylindrical formations.

11. The combination in a sifter of a plurality of nested cylindrical screens, a cylindrical agitator nested within the inner screen, agitator formations associated with 35 the screens for effecting agitation of material between the screens with relative angular movement of the screens, closures and hand holds at respective opposite ends of the screens, said agitator and screens being 40 alternately secured with respective hand holds at respective opposite ends of the screens, and bearings at the free ends of said agitator and screens for supporting said agitator and screens with respect to adjacent 45 screens for relative angular movement and adapted to prevent material passing by the screens at the ends thereof.

12. The combination in a sifter of three nested cylindrical screens, a cylindrical agitator nested in the inner screen, agitator formations associated with the screens for effecting agitation of material between the screens with relative angular movement of the screens, cylindrical hand hold formations at respective opposite ends of the screens and formed integrally with respect to the two outermost screens, a third cylindrical formation at one end of the inner screen and formed integrally therewith and 60 frictionally engaged in the cylindrical for-

mation of the outermost screen whereby the inner and outer screens are secured together, a fourth cylindrical formation at one end of the agitator and formed integrally therewith and frictionally engaged in the cylindrical formation of the intermediate screen whereby the agitator and intermediate screen are secured together, bearings at the free ends of the agitator and screens for supporting the agitator and screens with respect to adjacent screens for relative angular movement and adapted to prevent material passing by the screens at the ends thereof and adapted to permit removal of the agitator and intermediate screen from the 75 inner and outer screens, circular closures frictionally engaged in said cylindrical hand hold formations, and an exterior handle on one of said closures for removing the same 80 to fill the sifter.

13. The combination in a sifter screen of a cylindrical sheet metal frame provided with a plurality of openings therein and formed by striking out the metal of the frame at said openings with this metal attached to sides of the openings and bending the same on the adjacent portions of the frame whereby to form agitator formations and screening extending over the openings so formed and secured to the frame. 90

14. The combination in a sifter screen of a cylindrical sheet metal frame provided with a plurality of openings therein and formed by striking out the metal of the frame at said openings with this metal attached to the sides of the openings and bending the same over the adjacent portions of the frame whereby to form thickened agitator formations, and screening extending over the openings so formed and disposed 95 on the side of the frame wall upon which said struck up and bent over metal is disposed and secured to the frame.

15. The combination in a sifter screen of a cylindrical sheet metal frame provided with a plurality of longitudinally extending openings spaced around the same and formed by striking out the metal of the frame at said openings with this metal attached to the longitudinal sides of the openings and bending the same inwardly over the adjacent portions of the frame whereby to form thickened agitator formations, and screening extending around the frame on the inside thereof and over said openings and secured to the frame. 105 110 115

In witness whereof I hereunto affix my signature this 26th day of July, 1924.

RAYMOND D. SCHNOOR.
